4 Claims. (Cl. 166—25)

The present invention relates to methods for consolidating subsurface reservoirs in the vicinity of oil wells, gas wells and similar boreholes and more particularly relates to an improved thermal consolidation process wherein heat is applied to a reservoir in order to coke oil in contact therewith. In still greater particularity, the invention relates to a thermal consolidation process wherein an expendable liner is positioned in the wellbore, heat is applied to the reservoir through the liner, and the liner is thereafter at least partially destroyed in order to restore communication with the reservoir.

Many subsurface oil and gas reservoirs are located in formations made up of unconsolidated or loosely consolidated sand particles. When a well drilled into such a reservoir is placed on production, the fluids entering the wellbore carry entrained sand particles with them. These particles tend to settle in the wellbore and clog it, necessitating workover operations at frequent intervals. Particles which do not settle in the wellbore and instead are entrained in fluids pumped to the surface cause excessive wear and erosion of pumps, tubing and other apparatus. Erosion of sand from the formation by the producing fluids may lead to undermining about the wellbore and cause the subsidence of overlying strata. When this occurs, the tubing or casing may be bent or, in some cases, completely collapsed. This sometimes necessitates abandonment of the well, or makes it necessary to perform an expensive sidetracking and redrilling operation. Subsidence of the overlying strata may permit the entry of foreign fluids into the producing reservoir or, particularly in the case of gas wells, permit substantial quantities of the reservoir fluid to escape into higher reservoirs outside the producing zone.

A number of methods designed to prevent the influx of sand particles into wells completed in unconsolidated reservoirs and thus alleviate the difficulties outlined above have been suggested in recent years. A particularly attractive method involves heating the unconsolidated zone about the wellbore to temperatures sufficient to coke oil in the formation and cement the particles together. Experimental work and field test have shown that this method can result in a highly permeable, well-consolidated area about the wellbore. There are certain problems which must be overcome, however. The presence of fluids in the wellbore during the heating step gives rise to convection currents which carry much of the heat away from the unconsolidated zone and prevent the attainment of temperatures necessary for consolidation. Oil which may be present in the wellbore tends to segregate into light ends which are carried upwardly by the convection currents and heavy components which settle about the heating unit. The heavy constituents of the oil generally coke much more rapidly than do the lighter materials and hence a thick layer of coke tends to form about the heater near the base of the producing zone. This may cause the heater to become stuck in the wellbore.

The present invention provides a new and improved thermal consolidation process which circumvents the difficulties set forth above. In accordance with the invention, it has now been found that the use of an expend-

able liner in the wellbore opposite the zone to be consolidated permits the application of heat to the reservoir from within the liner without the establishment of convection currents in the wellbore and without danger of cementing the heater in place. The heat applied to the reservoir can be controlled to better advantage so that in most cases the time required for coking is greatly reduced. The use of a liner which can at least in part be destroyed by chemical, thermal or other methods after coking has been completed, without injuring the consolidated structure, permits fluids to be produced from the formation without difficulty.

The liner employed in carrying out the process of the invention may be constructed of a variety of different metals having melting points in excess of the coking temperature. Metals which can readily be destroyed by treatment with chemical agents without damaging the consolidated formation surrounding the wellbore are generally preferred. Representative examples of such metals and chemical treating agents which rapidly attack them are shown in the following table.

	Metal	Chemical Agent
25	Aluminum	1 N Sodium Hydroxide. 35% Hydrochloric Acid. 100% Propionic Acid. Mixed 50% Sulfuric Acid—50% Nitric Acid.
	Magnesium	15% Nitric Acid. 15% Hydrochloric Acid. 15% Sulfuric Acid.
30	25% Nickel—75% Iron Alloy	55% Nitric Acid.
	Copper	55% Nitric Acid. 15% Ammonium Hydroxide.
	Brass	55% Nitric Acid. 40% Hydrochloric Acid.
35	Nickel Bronze	15% Ammonium Hydroxide. 25% Phosphoric Acid.

It will be understood that the above metals and chemical agents are merely representative and that other metals, other agents and other concentrations may be employed in carrying out the invention.

In addition to metals which are subject to chemical attack, metals that melt at temperatures slightly higher than the coking temperature may be utilized for carrying out the process of the invention. By rapidly increasing the wellbore temperature following completion of the coking operation, the metallic liner can be melted to complete the well. Suitable metals and their melting points include the following.

	Metal	Melting point, ° F.
50	Aluminum	1220
	Magnesium	1202
	30% aluminum—70% copper alloy	1391
	50% sodium—50% bismuth alloy	1274
55	50% copper—50% tin alloy	1256
	20% copper—80% zinc alloy	1292
	90% lead—10% tellurium alloy	1310
	90% aluminum—10% antimony alloy	1382
	80% aluminum—20% zinc alloy	1148
60	90% aluminum—10% tin alloy	1193
	33% copper—67% zinc alloy	1463
	40% copper—60% zinc alloy	1544

Crude oils can readily be coked at temperatures between about 600° F. and about 1500° F. The optimum coking temperature will depend somewhat upon the composition of the oil and the pressure conditions in the borehole. As indicated by the above table, a variety of metals and metal alloys melting at temperatures between about 1000° F. and about 1650° F. are available and may be utilized in the practice of the invention. The particular metal employed will, of course, depend upon the coking temperature utilized.

The configuration of the liner used in carrying out the process of the invention will depend in part upon the metal employed and in part upon the method, chemical or thermal, to be used to render the liner permeable following the coking operation. Because many metals otherwise particularly suitable for purposes of the invention lose much of their strength at temperatures in the coking range, it is generally preferred to employ an inner perforated liner of alloy steel or ceramic material provided with an outer layer or sheath of the metal to be chemically or thermally removed. In other cases, a liner containing one or more plugs or sections of metal which may be removed by chemical or thermal means will be preferred. In still other instances, however, a homogeneous liner may be used.

In carrying out the process of the invention, a liner which can be totally or in part removed by chemical or thermal means is first lowered into the wellbore opposite the unconsolidated formation. The wellbore may contain casing which has been perforated opposite an unconsolidated producing zone or instead may be open opposite the unconsolidated zone. In a wellbore of the first type, the liner will normally be suspended at the lower end of a string of producing tubing and a heat-resistant packer will be placed between the casing and tubing above the liner. In a wellbore open opposite the unconsolidated formation, the liner may be connected to and supported by the lower end of the casing. After the liner has been set in place, a borehole heater of the chemical, electrical or combustion type is lowered into the liner. Heat is then applied to the reservoir through the liner wall. The lighter constituents of the oil surrounding the liner are vaporized by the heat and forced into the formation. The heavier components which remain in the formation in the area adjacent the liner are converted into coke. The coking which thus occurs consolidates the formation. After coking has been completed, the liner is at least in part destroyed by rapidly increasing the wellbore temperature or by removing the heater and introducing a chemical agent into the liner. If heat is used to melt the liner, the molten metal will flow into the bottom of the wellbore and solidify after the heater has been removed. Where a slotted liner containing fusible plugs is employed, a gas or other fluid can often be injected into the well in order to force the metal out into the formation after it has softened. If a chemical agent is used to dissolve at least part of the liner, it may be pumped down the well casing or tubing or instead may be injected through a corrosion-resistant hose or string of tubing lowered into the well for that purpose. Many acids and bases suitable for use in the practice of the invention have little or no effect upon alloy steel well tubing and casing and do not require that particular precautions be taken. It is frequently advisable, however, to inject a neutralizing agent after the liner has been dissolved in order to prevent corrosion of equipment with which the initial fluids produced from the well may come into contact.

The process of the invention is particularly useful as a means for completing wells drilled into unconsolidated oil-producing reservoirs but may also be utilized in reservoirs which contain little or no oil. It is sometimes desired to complete wells in unconsolidated water sands or gas reservoirs, for example, and in such cases sufficient oil to permit coking may be injected into the reservoir before the liner is installed. It is preferred that the oil thus injected be a heavy, low gravity oil which can readily be coked at relatively low temperatures. The amount necessary to saturate the formation for several feet in the vicinity of the wellbore can easily be computed.

The exact nature and objects of the invention can be more fully understood by referring to the following detailed description of several specific embodiment thereof and to the accompanying drawings, in which:

FIG. 1 represents in vertical section a wellbore open opposite an unconsolidated producing zone wherein an expendable liner has been connected to the lower end of the casing and cemented in place;

FIG. 2 is a vertical section through the wellbore of FIG. 1 after the cementing plugs have been removed and the heater has been suspended inside the liner to start the coking operation;

FIG. 3 depicts in vertical section the wellbore shown in FIGS. 1 and 2 after coking has been completed and the liner has been destroyed.

FIG. 4 is a vertical section through a cased and perforated wellbore containing an expendable liner and heater useful in the practice of the invention;

FIG. 5 is a partial view of the wellbore of FIG. 4 showing an alternate method for closing off the lower end of the liner employed in the practice of the invention;

FIG. 6 illustrates in vertical section a wellbore containing a slotted liner fitted with an expendable outer sleeve; and,

FIG. 7 is a vertical section through a wellbore containing a slotted liner provided with plugs of a lower melting point metal more susceptible to attack by chemical agents than the base metal of the liner.

Turning now to FIG. 1, reference numeral 11 designates a wellbore drilled into an unconsolidated oil-producing reservoir beneath the earth's surface. Casing 12 has been installed in the upper part of the wellbore above unconsolidated zone 13. Collar 14, attached to the lower end of the casing before it is lowered into place, supports cementing plug 15 of brass, aluminum or other drillable material and cementing basket 16 carried on the outside of the casing. A cement basket of the type suitable for this purpose is shown on p. 2212 of the 1958-59 Composite Catalog and can be furnished by Halliburton Oil Well Cementing Company, Duncan, Oklahoma. Ports 17 above the cementing plug extend through the casing wall to permit the passage of cement into the annular space between the casing and borehole wall above the basket. Upper plug 18 has been provided above the cement 19 within the casing to facilitate pumping of the cement downwardly therein. A plug of this type is also readily available from the Halliburton Oil Well Cementing Company in Duncan, Oklahoma, and is shown on page 2211 of the 1958-1959 Composite Catalog. As shown in FIG. 1, the cement has been circulated down the casing and up the annular space and has been allowed to set.

Liner 20 of brass or a similar metal which can be fused at temperatures somewhat above the coking temperature or dissolved with an acidic or basic reagent is attached to the lower end of collar 14 below cementing plug 15. The liner may be corrugated or otherwise shaped to increase its resistance to external pressure. In lieu of a continuous liner having a rounded bottom as shown in FIG. 1, a liner consisting of a metallic sleeve fitted with a suitable cap or plug at its lower end may be utilized. The collar 14 may be an integral part of the liner if desired.

After the casing and liner 20 have been installed in the wellbore as discussed in the preceding paragraph, the cementing plugs 15 and 18 and the cement remaining therebetween are drilled out in the conventional manner. An electrical heater 21 supported by an armoured cable 22 or other suitable heating device is then lowered into the liner as shown in FIG. 2 of the drawing. The heater is turned on and heat is transmitted to the formation by conduction and radiation. Thermocouples, not shown, may be installed on the inner wall of the liner for purposes of temperature control if desired. Heat reaching oil in the wellbore outside the liner and in the surrounding formation results in vaporization of the lighter constituents of the oil. The vaporized materials are forced into the formation, leaving the heavier components of the oil behind. These are converted into coke 23 which

serves to bond together the particles making up the formation. The liner and the cement between the casing and formation wall prevent excessive heat losses, gravity segregation and other difficulties which might otherwise arise in the coking process. The time required for the formation of sufficient coke to consolidate the unconsolidated zone will depend largely upon the characteristics of the oil in the reservoir and the coking temperature utilized. The coking rate under a particular set of conditions can readily be determined in advance by coking samples of the oil at the surface under simulated wellbore conditions.

Upon completion of the coking operation as described above, the liner shown in FIGURES 1 and 2 is at least in part destroyed by treating it with nitric acid or a similar reagent. A tube of Teflon or other corrosion-resistant material may be inserted in the wellbore to convey the acid or other reagent into the lining in the event that a reagent highly corrosive to steel casing is used. The elevated temperature of the liner following the coking operation accelerates reaction between the liner metal and the reagent and results in rapid destruction of the liner. Tests have shown that petroleum coke formed in the wellbore in the manner described herein is relatively inert with respect to acids and bases and that permeability is not appreciably affected during the destruction of the liner. A neutralizing reagent can be pumped down the wellbore after the liner has been destroyed in order to counteract any reagent which may have contacted the casing or may remain in the bottom of the well. The wellbore following destruction of the liner is shown in FIG. 3 of the drawing.

Reference is now made to FIG. 4 of the drawing which depicts a cased and perforated wellbore containing an expendable liner and an electrical heater useful in the practice of the invention. Casing 26 extends below the unconsolidated producing zone 27 and has been cemented in place in the conventional manner, the cement being designated by reference numeral 28. Perforations 29 penetrate the casing and cement opposite the producing zone. In the practice of the invention in such a wellbore, an expendable liner 30 of aluminum or a similar metal is lowered into the wellbore and held in place opposite the producing zone by means of a conventional packer or other anchoring device 31. A typical liner 45 hanger and packer assembly is shown on page 4848 of the 1958-59 Composite Catalog and is available from the Texas Iron Works, Inc., of Houston, Texas. If a packer is employed, it will preferably be constructed of asbestos or other heat resistant material. A conventional packer of rubber or the like positioned a sufficient distance above the perforated section of the casing to avoid damage due to high temperatures may be used in some cases, however. After the liner has been installed, and the hole bailed substantially dry, electrical heater 32 is lowered into place opposite the unconsolidated formation and is used to coke oil present therein. Following the coking operation, the heater may be withdrawn and the liner filled with a chemical agent to effect its destruction. The chemical agent can be spotted in the liner by using a string of tubing extending from the bottom of the liner to the surface. The wellbore and tubing above the chemical agent can be filled with oil or salt water to maintain pressure control when communication between the formation and the wellbore is restored.

FIG. 5 of the drawing is a partial view of the wellbore of FIG. 4 showing an alternate method for closing off the lower end of the liner employed in accordance with the invention. As indicated therein, the liner 30 may be simply a cylinder of suitable metal open at the lower end. Cement 33 may be placed in the bottom of the wellbore about the end of the liner in order to close it. The use of cement as shown anchors the liner and prevents it from moving upwardly in the borehole when the fluid level therein is reduced by swabbing.

In FIG. 6 of the drawing is shown a liner assembly consisting of an inner slotted liner 34 of alloy steel, ceramic material or the like which is resistant to heat and chemical attack and an outer sleeve 35 of aluminum or a light metal which can be destroyed by chemical or thermal means. The slotted liner supports the outer sleeve against the formation pressure and thus permits the use of metals in the sleeve which would otherwise be unsuitable because of their low strength at elevated temperatures. The width of the slots in the inner liner will depend somewhat upon the particular metal employed in the sleeve. In general, slots from about $\frac{1}{16}$ to about $\frac{1}{2}$ inch in width will be satisfactory. If the outer sleeve and the slotted liner are made of metals having similar coefficients of thermal expansion, they may be welded to one another as shown in the drawing. In other cases, suitable collars and asbestos packing may be used to connect the two and accommodate different rates of thermal expansion.

Casing 36 has been set and cemented in place in the wellbore shown in FIG. 6 of the drawing. The cement is designated by reference numeral 37. Perforations 38 have been made opposite the unconsolidated formation. The liner assembly is connected to production tubing 39 by collar 40 and is suspended adjacent the perforations. Packer 41 of asbestos or other heat-resistant material is positioned between the production tubing and casing above the liner assembly. The packer is not always essential, however, and in some cases can be dispensed with, particularly where the annular section of the wellbore is filled with gas and maintained under sufficient pressure to prevent the influx of fluids from the reservoir.

Heater 42 is lowered through production tubing 39 into the liner assembly shown in FIG. 6 in order to consolidate the formation. Upon completion of the coking operation, the outer sleeve of the assembly can be dissolved chemically in the manner described heretofore, or it can be melted by raising the temperature above the melting point of the material in the outer sleeve. The inner liner of the assembly remains in the borehole after the outer sleeve has been at least partially destroyed and, particularly in the case of the wells which are not cased opposite the producing zone, affords added protection against the influx of solids into the tubing with the producing fluids should the consolidated zones about the wellbore subsequently fail.

FIG. 4 of the drawing illustrates a further method of carrying out the process of the invention wherein a liner containing plugs of a fusible or soluble metal is used. As shown in FIG. 7, liner 43 of steel or other high melting, corrosion-resistant material contains slots or openings filled with plugs 44 of aluminum, magnesium, copper or other material which can be readily melted or dissolved with acid or a caustic solution. A convenient method of fabricating the liner is to drill holes in a steel pipe and plug them with rivets of aluminum or the like. A cap can be welded or threaded onto the lower end of the pipe. The liner is supported in the wellbore by a packer or similar anchoring means 45 which engages casing 46 above the unconsolidated producing zone. The cement behind the casing is designated by reference numeral 47. Heater 48 at the end of cable 49 is lowered into the liner in order to coke the formation and may be thereafter utilized to melt plugs 44 in the liner. An acid or base may instead be employed to dissolve the plugs.

The invention is further illustrated by the results of tests carried out to determine the effectiveness of the process. In the first test, an 18° API gravity Bayou Choctaw crude oil was coked in unconsolidated sand packed around a 7-inch perforated cemented casing located in a shallow 16-inch borehole. The coking operation was carried out by first positioning a 4½ inch steel liner inside the casing opposite the 10-foot perforated section. The annular space between the casing and liner

was filled with crude oil and then blocked off above the perforations. An electrical heater 3 inches in diameter and 10.8 feet long was positioned inside the liner opposite the perforations and energized. A period of about 4½ hours was required to vaporize the oil in the annular space and drive it through the perforations into the sand. During this period the heater temperature, as indicated by thermocouples attached to its outer surface, gradually increased to about 1520° F. The power to the heater was thereafter decreased at intervals to maintain a constant temperature. Heating was continued for 24 hours after the oil in the wellbore had been vaporized. The heater was then turned off and the borehole was allowed to cool for several hours.

The heater, liner and cemented casing were raised from the borehole and examined. The sand surrounding the cemented liner had been coked for an average distance of about 1½ inches away from the liner. Next to the liner it was well consolidated. The coked sand was found to have an average permeability to oil of about 10,154 millidarcies and an average permeability to air of about 16,123 millidarcies. Measure of the compressive strength of the coked sand showed an average strength of about 456 pounds per square inch.

After the above test had demonstrated that the use of an electrical heater inside a liner is an effective means for coking oil in an unconsolidated formation, tests were carried out to determine the effectiveness of concentrated nitric acid for dissolving plugs of copper and brass ½ inch in diameter set in holes in the wall of steel tubing. The tubing containing the plugs was heated at 1200° F. for 24 hours and thereafter filled with the acid. It was found that the acid ate its way through the brass in about 20 minutes, while about 25 minutes was required to dissolve the copper.

The effect of acids and bases on coke formed by heating crude oil in the presence of unconsolidated sand was tested by soaking samples of the coke in 28% hydrochloric acid, concentrated sodium hydroxide and concentrated nitric acid for periods ranging from 23 days to 35 days. Neither the acids nor the caustic had any perceptible effect upon the coke.

The data obtained in the above-described tests clearly demonstrate that unconsolidated sands surrounding a wellbore can be consolidated by utilizing a heater inside a liner within the wellbore to coke oil in contact with the sands, that chemical reagents can be employed to dissolve copper and similar inserts in liners, and that the use of such reagents does not adversely affect the coke thus

formed. It is therefore apparent that the process of the invention provides an effective means for overcoming the difficulties encountered with unconsolidated sands in the past.

5 What is claimed is:

1. A process for consolidating an unconsolidated subterranean formation surrounding a borehole which comprises installing an impermeable liner in said borehole to prevent fluid communication between the borehole and said unconsolidated formation, said liner being at least in part readily fusible at a temperature in excess of a predetermined coking temperature; lowering a wellbore heater into said liner adjacent said formation; heating oil in said formation to said coking temperature by means of said heater until sufficient coke to consolidate said formation in the immediate vicinity of said borehole has been formed; and thereafter increasing the temperature in said borehole by means of said heater to at least partially fuse said liner and thereby restore fluid communication between said borehole and said formation.

2. A process for consolidating an unconsolidated subterranean formation surrounding a borehole which comprises installing an impermeable liner in said borehole to prevent fluid communication between the borehole and said unconsolidated formation, said liner being at least in part readily soluble in a selected chemical reagent; lowering a wellbore heater into said liner adjacent said formation; heating oil in said formation by means of said heater until sufficient coke to consolidate said formation in the immediate vicinity of said borehole has been formed; and thereafter introducing said selected chemical reagent into said borehole in contact with said liner to at least partially dissolve said liner and thereby restore fluid communication between said borehole and said formation.

3. A process as defined by claim 2 wherein said chemical reagent is an acid.

4. A process as defined by claim 2 wherein said chemical reagent is a base.
